DESIGN FOR A LIGHT SHADE FOR AN ELECTRICAL FIXTURE

Clyde D. McCann, Des Moines, Iowa

Application November 2, 1946, Serial No. 134,474

Term of patent 14 years

(Cl. D48—4)

To all whom it may concern:

Be it known that I, Clyde D. McCann, a citizen of the United States and a resident of Des Moines, in the county of Polk and State of Iowa, have invented a new, original, and ornamental Design for a Light Shade for an Electrical Fixture, of which the following is a specification, reference being had to the accompanying drawing, forming part thereof, in which:

Fig. 1 is a front view of a light shade for an electrical fixture, showing my new design;

Fig. 2 is a side view looking toward the left in Fig. 1;

Fig. 3 is a rear view;

Fig. 4 is a bottom plan view;

Fig. 5 is a top plan view of my new design; and

Fig. 6 is a sectional view on the line 6—6 in Fig. 3.

I claim:

The ornamental design for a light shade for an electrical fixture, substantially as shown.

CLYDE D. McCANN.
